UNITED STATES PATENT OFFICE.

MILTON R. LOUDEN, OF JERSEY CITY, NEW JERSEY.

DESIGN FOR A CARPET.

SPECIFICATION forming part of Design No. 12,415, dated August 16, 1881.

Application filed July 14, 1881. Term of patent 3½ years.

To all whom it may concern:

Be it known that I, MILTON R. LOUDEN, of Jersey City, in the county of Hudson and State of New Jersey, have invented a new and original Design for Carpets, of which the following is a specification.

This invention relates to a new and original design for carpets and similar fabrics; and it consists in the novel grouping and configuration of figures, hereinafter more fully described.

The accompanying photograph illustrates a face view of a carpet having my new design.

The figure C is a stripe containing the figure d, which is a band containing a pattern resembling small fir-trees set in a row, with circular globe-like figures below them, from which project downward a series of parallel lines. The stripe C also contains the band j, ornamented with a design resembling a bar, with knobs projecting at intervals.

The figure B is a stripe containing the band O, ornamented with a series of figures resembling clover-leaves set one upon or alongside of another. It also contains the band i, with an ornamentation of rectangular figures set close to one another.

The stripe A contains an ornamentation consisting of the figure E, composed of the leaf-like figures c and e and f, all having their stems meeting in the center of the figure E and forming a square, with indentations separating the several leaves.

The figure D consists of a triangular base, h, composed of figures resembling leaves, from the top of which extends the leaf-like figure g.

The figures E and D are alternated in the stripe A, and appear over the background p, consisting of a series of little figures resembling the capital letter T.

The stripe a contains an ornamentation 40 resembling a fence with closely set pointed pickets.

I claim—
